UNITED STATES PATENT OFFICE.

GUSTAV SAHMER, OF STRASSBURG, GERMANY.

DOOR-LOCK.

1,038,663.

Specification of Letters Patent. Patented Sept. 17, 1912.

Application filed October 5, 1911. Serial No. 652,898.

To all whom it may concern:

Be it known that I, GUSTAV SAHMER, a subject of the German Emperor, and residing at Strassburg, Alsace-Lorraine, German Empire, have invented certain new and useful Improvements in Door-Locks, of which the following is a specification.

The present invention has reference to improvements in door locks, and relates 10 more specifically to an electrically operated device for locking and freeing respectively the latch bolt of door locks, and the particular object of the invention is to provide means in connection with such electrically 15 controlled door locks whereby the lock-bar is mechanically secured in either end position, and is so constructed that a bending or breaking of it, upon the latch bolt encountering it in the "locked" position, is effectively prevented.

In order to make my invention more readily understood, I will now describe it with reference to the accompanying drawing, in which—

25 Figure 1 represents a side elevation of the device, with but part of the latch bolt and its casing; Fig. 2 shows a section on line A—B of Fig. 1; Fig. 3 shows a front view, with the front wall of the box removed; 30 Fig. 4 shows more diagrammatically a modified construction with yielding lock-bar; Fig. 5 represents a diagram of the circuit connections suitable in using the improved device.

35 Within the box 1 are secured in the support 2 the iron cores 3, 4 with their insulated wire coils 5, 6, whose outer wire ends 7, 8 are connected up to the leading-out binding posts 9, 10 which are suitably secured in the wall of the box. The other wire ends 11, 12 lead to a common post 13. An armature 14 (Fig. 2) can be freely reciprocated between the two coils on the guide rod 15 rigidly secured in the support 40 2, and is secured to the lock-bar 16, which latter can reciprocate in the support 2 and also in a guide plate 17, preferably stamped out of the wall of the box and bent rectangularly thereto, which plate also serves 45 as protecting shield for the operating parts. Upon a second rod 18, secured in the supporting frame 2, is pivoted by means of the

sleeve 19, or in any other suitable manner, a rocking armature which is acted on by the spring 20. This armature, in the shape 55 of a bell-crank, partly surrounds with its forked arm 21 (Figs. 2 and 3) the cores 3, 4, and with its other arm 22 takes into two notches 23 in the lock-bar 16, spaced apart to correspond to the two respective end positions of the lock-bar.

In order to prevent bending or breaking of the head of the reciprocating lock-bar upon the bolt 24 being shot and the lock-bar being already in the "locked" position, its 65 side facing the bolt and the lower front edge of the bolt are rounded off, as shown in the modified form of the described device as illustrated in Fig. 4, and the bar itself is composed of two relatively movable parts, 70 the tubular member 25 and the locking-member proper 27 guided therein and acted on by the spring 26. Suitable means, for instance a slot and pin arrangement as at 75 35, prevent rotation of the lock bar. The reduced end 28 of the locking member 27 80 is guided in the support 2, and the armature 14 is rigidly secured to the tubular member 25. Upon the bolt striking the projecting lock-bar head the rounded-off faces easily 85 glide over one another, the locking member readily receding under compression of the interposed spring 26, until the bore 36 in the bolt registers with the lock-bar head, when the latter under the action of the 90 spring is forced forward into the bore and thus locks the bolt against inadvertent withdrawal. In this modified construction there is shown a flange 29 on the tubular member, which fulfils the same office as the notches 95 23 above described with reference to Figs. 1 and 2, and which co-operates with the arm 22 of the rocking armature for the purpose of securing the lock-bar in the respective end position.

I will now describe the operation of the device in connection with the diagram shown in Fig. 5. The two-way switch 30 with its contacts *a* and *b* is connected-up respectively to the coils 5, 6, and its contact 100 *c* to the battery 31 and the latter in turn to the common terminal 13. By operating the switch, either one of the electromagnets 3, 4 may be energized and the armature corre-

spondingly attracted. Suppose the circuit be closed over 30^c, 30^a, 5, 13, 31, 30^c, then coil 5 is excited and the armature 14 is attracted by the magnet 3, advancing the lock-bar 16 and causing its head to take into the bore 36 of the shot bolt 24 and securely locking the latter against inadvertent withdrawal. For releasing the bolt, the circuit is to be closed over 30^b, when the coil 6 is excited and its core 4 attracts the armature, causing the latter's head to free the bolt 24. Simultaneously with the armature 14 the forked end 21 of the rocking armature is attracted, its other end 22 being lifted out of the respective notch 23 in the lock-bar. Upon interruption of the current the spring 20 presses the armature end 22 back again into the other notch, whereby the lock-bar is again secured in the respective new end position.

In the modified construction shown in Fig. 4, the operation is similar to that just described, the arm 22 of the rocking armature taking over or under the flange 29 of the tubular member 25, as the case may be.

In the circuit illustrated in Fig. 5 there are further cut-in the two-way switch 32, the door contact 33, and the loose key switch 34. Now suppose the door bolt 24 is to be locked automatically upon the door being shut on going out or coming in, without the switch 30 being operated in any way, and the locking device being in the "open" position; then the switch lever S of switch 32, which ordinarily is in the inactive position shown, is to be laid onto contact *d*, when, upon the door operating the door contact 33, the current will pass through line V, over the contact member 33', of the door contact, through line VI and post 9 to the upper coil 5, through post 13, line II, battery 31, line III, and back to switch 32, which completes the circuit. The coil 5 attracts the armature and the lock bar 16 enters the recess in the bolt 24 and thereby locks the latter. Suppose now that the person going out or wanting to enter the door has no access to the switch 30, then it would be impossible to operate the device for locking and unlocking, and it is therefore necessary to connect-in the loose key switch 34. The person going out must connect the lever S with contact *e* whereby the switch 34 is cut into the main circuit. Upon inserting the key into the rotary part 34', of the switch and turning it, the contact member *f* is lifted and contacts with the rigid contact member *g*, so that the current now passes from post *e*, through lines VII and VIII to the lower coil 6, middle post 13, line II, battery 31, line III back to the switch 32; the armature 14 is attracted by the coil 6 and the lock bar 16 is withdrawn from the bolt 24. The posts *e* and *d* of the switch 32 are interconnected for the

purpose that the contact 33 and the loose key switch may respectively operate, no matter what the contacting position of the lever S. Obviously, the two-way switch 30 can be operated at any time, independently 70 of any position or operation of the auxiliary devices described. The operation of the device for freeing the lock-bolt may also be brought about mechanically by providing a push button 37 in connection with the 75 box (Fig. 2), operable from without, which acts on the rocking armature so as to lift its arm 22 out of the lower notch or from under the flange 29 of the lock-bar, when the latter will drop down by its own weight 80 and release the bolt.

What I claim is:—

1. The combination with a lock comprising a reciprocating bolt, of a lock bar, coaxially arranged electromagnets, an armature thereto, secured to said lock bar and adapted to move said lock bar into or out of coöperation with said bolt, and electromagnetically controlled means for securing said lock bar in either operative end position.

2. The combination with a lock comprising a reciprocating bolt, of coaxially disposed electromagnets, a reciprocating armature thereto operating between said electromagnets and axially thereof, a lock bar operated by said armature and coöperating with said reciprocating bolt in the one end position, and electromagnetically controlled means for securing said lock bar in either 100 end position.

3. The combination with a lock comprising a reciprocating bolt, of coaxially disposed electromagnets, a reciprocating armature thereto operating axially thereof, a lock bar operated by said armature and coöperating with said reciprocating bolt, and a rocking armature operated by said electromagnets and coöperating with said lock bar for securing it in either operative end position.

4. The combination with a lock comprising a reciprocating bolt, of a lock bar, stop means thereon, electromagnets coaxially spaced apart, a reciprocating armature actuated by said electromagnets and secured to said lock bar, means for securing said lock bar against inadvertent operation consisting of a spring actuated rocking armature operated by said electromagnets and 120 coöperating with said stop means on said lock bar, and means adapted to cause part of the lock bar to recede to its unlocking position when the bolt is shot with the lock bar in the locking position.

5. The combination with a lock comprising a reciprocating bolt, of a lock bar, stop means thereon, electromagnets coaxially spaced apart, a reciprocating armature actuated by said electromagnets and secured 130

to said lock bar, electrically controlled means for securing said lock bar against inadvertent operation consisting of a spring-actuated rocking armature operated by said electromagnets and coöperating with said stop means on said lock bar, and manually operable means for actuating said rocking armature independently of the electrical

control, for the purpose of unlocking said bolt. 10

In testimony whereof I affix my signature in presence of two witnesses.

GUSTAV SAHMER.
